APPARATUS FOR CENTERLESS GRINDING OR POLISHING

Application filed January 20, 1927. Serial No. 162,300.

The present invention relates to methods and apparatus for centerless grinding or polishing and more particularly to methods and machines adapted for grinding or polishing taper work.

The object of the present invention is to provide a method and machine by which either taper or straight work may be ground or polished without the necessity of chucking the work or mounting it on centers.

With this object in view, the present invention consists in the method and machine for grinding or polishing as hereinafter described and particularly defined in the claims.

In the accompanying drawings, Fig. 1 is a side elevation, partly in section of a machine embodying the several features of the present invention; Fig. 2 is a front elevation showing so much of the machine as is necessary to an understanding of the present invention; Fig. 3 is a plan view of the machine shown in Figs. 1 and 2; Fig. 4 is a rear elevation of the work rest; Fig. 5 is a detail view 25 in section on line 5—5 of Fig. 3; Fig. 6 is a detail in section on line 6—6 of Fig. 1; Fig. 7 is a diagram in plan illustrating the operation of grinding or polishing with the machine of the present invention; Fig. 8 is a 30 diagram similar to Fig. 7 but taken in front elevation; Fig. 9 is a diagram in plan illustrating the operation of taper grinding without transverse feed; Fig. 10 is a front view of the belt tensioning mechanism; and Fig. 11 35 is a side view of the belt tensioning mechanism.

The preferred embodiment of the present invention comprises an improvement on the machine disclosed in the Blevney patent, No. 40 1,594,445, dated August 3, 1926, in which the grinding or polishing of straight work is effected by means of an abrasive element preferably in the form of a moving belt, the work being fed over a suitable work rest transversely of the abrasive element by a suitable work holding and feeding device. This device, which may consist of a rotating roll, serves the double function of peripherally supporting the work to maintain it in engagement with the abrasive element and

causing the transverse movement of the work, for which latter purpose the roll is inclined with respect to the center line of the work about an axis substantially perpendicular to the plane of the abrasive element.

The principal feature of the present invention consists in means whereby the work holding means is mounted to permit an automatic recession thereof from the belt in order to accommodate work of changing diameter as successive portions pass into engagement with the abrasive element. This feature permits the grinding of tapers, the work holding means automatically increasing its distance from above as the work passes through the machine.

In addition to the adjustment of the work holding means about an axis perpendicular to the abrading surface for the purpose of feeding the work, a further feature of the present invention contemplates an adjustment thereof about an axis which is substantially parallel to the abrading surface in order that its engagement with the work may conform to the work surface, particularly when tapers are to be ground or polished.

Referring to the drawings, the illustrated embodiment of the present invention comprises the abrasive belt 10 and the backing or cushion belt 12 which are caused to travel in the direction of the arrow of Fig. 1. The backing belt 12 passes over the platen bars 14 which are supported on a carrier 16, and mounted for suitable movement toward and from the belt as described in above mentioned Blevney patent. The work 18 is supported on a work rest indicated generally by 20 during the polishing or grinding operation, and is maintained in engagement with the belt by means of the rotating feed roll 22, constituting the work holding and feeding means. The feed roll is covered with leather or rubber and is rotated in the direction of the arrow in order to rotate the work and present all portions thereof to the belt. The feed roll 22 is mounted in a feed roll housing 24 and is rotated by means of gears 26 which are driven from a pulley 28 connected by a belt 30 with a source of power, the belt being maintained taut by a tension or take-

up means hereinafter to be described in detail. The feed roll housing is provided with bearings 32 to receive trunnions 34 extending from opposite sides of a vertical supporting plate 36. The feed roll housing may be adjusted to different angular positions by rotation about the axis of the trunnions 34 which axis, it will be seen, is perpendicular to the abrading surface of the belt 10. 5 The housing is maintained in adjusted position by bolts 38. This inclination of the feed roll is for the purpose of imparting a longitudinal motion to the work as it passes over the work rest. The details of the abrasive element and the feed roll thus far described are similar to those described in the above mentioned Blevney patent. 10

In order to permit grinding of tapers, provision is made for adjusting the feed roll about an axis parallel to the abrasive surface, that is to say, a vertical axis in the illustrated machine. Provision is also made for permitting a recession of the feed roll from its initial position during the grinding operation in order that the taper work with its changing diameter may pass over the work rest between the feed roll and the belt. 20

To these ends, the plate 36, which constitutes a support for the feed roll assembly, is formed with a base 40 to the bottom of which is secured a post 42 received in a suitable bearing in a carriage 44. The base 40 rests upon the top of the carriage 44, and is secured in any desired angular position by 30 means of a bolt 46 threaded into the carriage 44 and passing through an arcuate slot 48 in the base 40. In order to prevent accidental removal of the feed roll assembly from the machine, the post 42 is formed with an annular groove 50 into which extends the end of a screw 52 threaded into the front of the carriage 44. It will be seen that the center line of the post 42 is the axis about 40 which the entire feed roll assembly may be adjusted to accommodate tapers of varying degree. 45

The carriage 44 is adapted to slide horizontally toward and from the belt, and for this purpose a slide bearing 54 receives the carriage assembly. The slide bearing is formed with tracks 56 over which pass rollers 58 received in recesses 60 of the carriage. The rollers are provided with trunnions 62 which are received in semi-circular recesses 55 adjacent to the roller recesses 60. The carriage is accurately guided by guide pieces 64 and 66 which engage therewith, the former guide piece being formed integral with the slide bearing 54, and the latter being adjustably attached to the bearing by means of bolts 68 received in the bearing and passing through transverse slots in the guide 66. The guides engage with the carriage on inclined surfaces to maintain the carriage in proper vertical position. One of the guides is cut 60

away to provide a locking piece 70, which may be forced against the side of the carriage by means of a hand screw 72 to retain the carriage in any desired adjusted position, as in the grinding or polishing of straight work where no movement of the carriage is necessary. A curtain 73 secured to the carriage and passing over a roller 74 journaled in the forward end of the slide bearing protects against entrance of dust into the moving parts. The free end of the curtain is provided with a weight 75 to hold it taut. 70

The supports for the various parts are described as follows: The slide bearing 54 is bolted to a table 76 extending transversely across the machine and the table is secured to a plate 77 which is formed integrally on the end of a vertical post 78. The post extends through a hole in a block 80 and the table with its associated mechanism is supported on the block by a collar 82, which is locked to the post 78 by a set screw 84. The block 80 is firmly supported upon the main column 86 of the machine by two posts 88 which are secured to the column, and on which the block 80 is slidably mounted. In order that the entire assembly may be adjusted toward and from the belt, a rotatable screw 90 is received in the block 80 and has its end journaled in a bracket 92 secured to the column 86 between the two posts 88. A hand wheel 93 is used to impart rotation to the screw in order to adjust the position of the table and its associated mechanism with relation to the belt. A curtain 94 similar to the curtain 73 is attached to the rear end of the carriage to protect the guides. 95

In order to maintain the feed roll in proper position with respect to the work and to the belt as the grinding proceeds, a cord 95 is secured to the rear end of the carriage 44 by means of a bolt 96 which is received in a slot in the carriage. From the rear end of the carriage the cord draws forwardly and passes over a pulley 98 downwardly to a second pulley 100 and thence to the left side over a pulley 102 journaled in the extreme left-hand end of the table. A weight 104 is attached to the end of the cord and acts to draw the carriage and its associated feed roll assembly toward the belt. The weight, being placed in the position shown, also serves to counter-balance the feed roll assembly and to prevent unbalancing of the table which might impart excessive stresses to the supporting posts. A stop 106 which projects upwardly through a slot 108 in the bottom of the guide limits the forward movement of the carriage by engaging with the rear end of the latter. The stop is provided with a horizontal plate 109 which bears against the under surface of the guide and which is secured in any desired position by means of a bolt 112 passing upwardly through the slot 108 and en- 100 110 115 120 125 130

gaging with a nut 114 which has a portion closely fitting in the slot 108.

The work rest and its mounting are described as follows: Secured to the front end 5 of the table is a plate 116 which is formed integrally with a bushing 118. The work rest supporting post 120 is received in the bushing and has circular rack teeth 122 formed on its lower end. The circular rack engages with 10 a pinion 124 which may be rotated by a hand wheel 126 to raise or lower the post 120. Moreover, the post may be rotated about its axis to present the work rest in various angular positions with respect to the belt. The 15 bushing is slotted transversely at 128 and also longitudinally in order to provide means for clamping the post 120 through the medium of a lock screw 130 as will be obvious. The post extends outwardly from the table at such 20 an angle that racking of the post will produce a horizontal movement of the work rest which is about one-half of the vertical movement. A mounting plate 132 is secured at the upper end of the post 120 and a work rest support 25 133 is pivoted on the mounting plate by means of a stud 134, provision being made for locking it in any adjusted position by means of a bolt 136 secured in the mounting plate and passing through an arcuate slot 138 30 in the support. The bolt 136 is positioned beyond the outer edge of the abrasive belt, where it is conveniently accessible for adjustment. The work rest proper consists of a plurality of freely rotatable rolls 40 mounted 35 on a pintle 142 which is journaled in a frame 144 secured by screws 146 to the support 133. The rolls are maintained in spaced relation by intermediate projections 147 formed integral with the frame 144.

40 The work rest is therefore capable of four adjustments,—first, a combined vertical and horizontal movement accomplished by racking the supporting post up or down; second, a horizontal movement effected by bodily adjustment of the machine bed by actuation of 45 the hand wheel 93; third, an inclination on the pivot 134 which is on an axis perpendicular to the abrading surface; and fourth, an angular adjustment between the plane of the 50 work rest and the abrading surface accomplished by rotating the supporting post 120 in its bushing.

55 The first of these adjustments is of especial value in grinding straight work, because if the diameter of the work is changed, the work rest may be moved in one operation to a position which is horizontally the correct distance from the belt and vertically correct to position the center line of the work 60 at the proper level. If it is desired to make independent vertical and horizontal adjustments, the rest is first moved to its proper vertical position by the supporting post, and its horizontal position is determined by the 65 second of the above mentioned adjustments.

The adjustment about the pivot 134 is of importance in fine polishing, as will herein-after be described. As for the fourth of these 70 adjustments, it will be noted that a rotation of the post 120 will produce a corresponding tipping of the work rest due to the inclination of the post from the vertical, but this tipping is ordinarily of no consequence, and if necessary, may be compensated by an adjustment on the pivot 134.

75 In the operation of the machine the platen bars 14 are brought up against the belt and are secured in position as described in the Blevney patent. For grinding straight work, the operation is identical with that described 80 in the Blevney patent. The work rest is adjusted so that the center line of the work is slightly lower than the center of the feed roll. The feed roll carriage is maintained stationary by means of the screw 72. The work 85 rest is positioned somewhat closer to the belt than to the feed roll in order that the work may not be jammed or cramped between the work rest and the belt. In order to cause feeding of the work through the machine, the feed roll is tilted on the trunnions 34, the axis of rotation of the roll, however, being maintained parallel to the abrading surface. It is to be noted that for adjustment to different sizes of straight work, it is preferable 90 to move the table as a unit by means of the hand wheel 93 rather than to move the carriage by loosening the screw 72. This operation moves both the feed roll and the work rest as a unit toward or from the belt, but if 95 the changes are such as to necessitate independent adjustments of the feed roll and the work rest, they may be effected by moving the feed roll carriage in the slide bearing and by racking the work roll supporting post up or 100 down.

105 For grinding taper work, the machine is adapted for use in two ways,—first, with transverse feeding of the work; and second, without feeding. In the first case, the parts 110 are arranged as diagrammatically shown in Figs. 7 and 8. The work rest may be adjusted to any suitable position about the pivot 134, being arranged for the operation illustrated 115 in Fig. 8 so that the axis of the work is horizontal. The plane of the work rest is parallel to the belt as indicated by the dotted line 200 in Fig. 7, and is positioned between the belt and the center of the smallest diameter of the work to be ground, in order that the 120 work may not be cramped or jammed by falling between the work rest and the feed roll. Vertically the work rest is arranged so that the center of the largest diameter of the work to be ground will be at a level not higher than the axis of rotation of the feed roll. The feed roll is adjusted about its horizontal and vertical axes which are respectively designated at 202 and 204 of Figs. 7 and 8. Adjustment about the vertical axis 204, which 125 130

is the axis of the bearing post 42, is made so that the angle of the feed roll with respect to the belt may be made to conform to the surface of the taper as shown in Fig. 7. The amount of inclination on the horizontal axis 202 is sufficient so that the axis of rotation of the feeding roll and center line of the work are oblique to each other, the rate of feeding being determined by the inclination between these lines. Although the engagement of the work and the feed roll is a point of contact because of the inclination of the roll with respect to the axis of the work, the adjustment of the roll about its taper axis 204 insures a uniform pressure of the work against the belt during the entire grinding operation. The carriage is unlocked by loosening the screw 72 and the stop 106 is adjusted to such a position that at the commencement of the grinding operation the feed roll will be at a distance from the belt exactly sufficient for receiving the small end of the work. The work is preferably started with a considerable portion of its length in engagement with the abrasive belt.

As the grinding progresses, the feed roll performs the two-fold function of holding the work against the belt and advancing it from left to right. As the work advances, it moves with its axis always parallel to itself, and because of the increasing diameter of the work, the feeding action causes the feed roll carriage to be moved forwardly or away from the belt, being pressed firmly against the work, however, by the action of the weight 104. The work is therefore moved transversely of the feed roll, and the feed roll is moved longitudinally by the work. The relative positions of the work and the feed roll are shown in full lines in Fig. 7 for the commencement of the grinding operation and in dot and dash lines for the condition when the work has progressed part way through the machine. At the commencement of the operation, the point of contact of the feed roll and the work occurs at the small diameter of the latter, and as the grinding proceeds this point of contact occurs on lower levels with respect to the work axis and on higher levels with respect to the feed roll axis. It is desirable that the point of contact be maintained at a level not higher than the axis of the feed roll for all positions of the work, in order that the roll may not have any tendency to force the work upwardly out of engagement with the work rest. At the completion of the operation, the work is automatically discharged from the right-hand side of the machine and the carriage is restored to its original position in readiness for another grinding operation by the action of the weight.

Employment of the machine to grind taper work without feeding is useful in cases where the work has projections which would pre-

vent passage thereof through the machine or where the work is of extreme taper. In this case, the parts are placed as shown in Fig. 9. The work rest is preferably arranged at an angle with respect to the belt as shown by the line 200 which is parallel to the center line of the work but somewhat nearer the belt than the feed roll. The feed roll is adjusted about its vertical axis 204 so that it contacts substantially throughout its entire length with an elemental line of the taper. This may require that the axis of rotation be maintained substantially horizontal, that is, without tilting on the axis 202, but, especially in the case of large tapers, it may be adjusted to lie parallel to the center line of the work, and at an angle from the horizontal. The feed roll carriage is preferably locked in position by the locking piece 70. In this operation, no transverse feeding action takes place, the feed roll merely rotating the work against the abrasive element. Because of the fixed position of the feed roll carriage, this operation permits grinding of tapers with considerable accuracy, although the length of the work which can be successfully ground is limited by the width of the belt.

While the work rest is preferably maintained horizontal for normal work, the pivotal adjustment on the stud 134 is a feature of importance for permitting fine polishing on soft metals such as brass. In this case, it is desirable to perform a plurality of polishing operations and to cross the polishing lines. To this end, the work is first fed through the machine with the work rest in a substantially horizontal position and is passed through a second time after the rest has been adjusted into an angular position about the axis of the stud 134. This gives a high luster and eliminates any polishing marks on the work.

It will be apparent from the foregoing description that during polishing and grinding of taper work a considerable latitude of movement is required for the belt 30 because of the movement of the feed roll carriage and the necessary tipping of the feed roll. To the end that the belt 30 may be maintained taut under all conditions, the take-up means illustrated in Figs. 10 and 11 is employed. The belt 30 passing over the feed roll pulley 28 is driven by a pulley 160 fast on a shaft 162 which is journaled in a bracket 164 secured by a post 166 to the main column of the machine. A driving pulley 168 connected with any suitable driving means is employed to rotate the shaft 162. An idler arm 170 formed integral with a hub 172 which is loosely received on the shaft 162, carries two spaced idler pulleys 174 over which the belt 30 passes. A counter balance arm 176 also formed integral with the hub 172, carries at its outer end a counter balance weight 178 which acts to maintain the idler pulleys in

engagement with the belt in a manner to maintain the belt taut under all conditions. The weight is pivoted on the arm 176 by means of a stud 180. The position of the part when the feed roll is in its rearward-most position, viz, its position nearest the abrasive belt, is indicated in full lines in Fig. 11. During the operation of grinding taper work, the feed roll carriage moves forwardly so that the feed roll pulley 28 may finally take the position indicated in dot and dash lines. The positions of the belt 30 and the counter balance arm are also illustrated for this position by dot and dash lines. It will be seen that by the employment of two spaced idler pulleys which are capable of simultaneous movement on the idler arm, the belt may be maintained taut by a movement of the idler arm which is only half of that which would be necessary if only a single idler were employed. Moreover, any possibility of a rubbing engagement between opposite sides of the belt upon a considerable movement of the carriage is avoided. Inasmuch as there is a considerable horizontal component of tension exerted by the belt on the feed roll assembly when the latter is moved considerably from the abrasive belt, it is desirable that the tension on the belt be relieved somewhat. This is accomplished by the raising of the counter balance arm 176 to a more nearly vertical position, where the counter balance 178 exerts a decreased tensioning force. In order to permit the counter balance to approach more closely this vertical position upon raising of the counter balance arm, the weight is grooved at 182 to provide a recess into which the arm may enter.

The above arrangement of the belt take-up mechanism provides for sufficient pressure of the idler pulleys against the belt for proper tensioning of the belt under all conditions independently of the movement of the carriage or of the tipping of the feed roll about any axis. The idler pulleys 174 are arranged sufficiently above the feed roll pulley 28, and the belt 30 is of sufficient length so that the belt may properly engage the groove of the feed roll pulley even though the latter is tipped to a considerable angle. In order to eliminate any possibility of disengagement of the belt and pulleys, however, the latter are formed with deep V-shaped grooves and the belt is of comparatively small cross section, fitting snugly within the grooves of the pulleys.

It will be seen that an important feature in connection with grinding of tapers consists in the provision for mounting the feed roll for adjustment about two axes, one of which is substantially perpendicular to the abrasive element, and the other of which is substantially parallel thereto. Stated in another way, the tipping axes of the feed roll

are mutually perpendicular and are substantially perpendicular to the axis of rotation of the feed roll.

It is to be understood that the invention is not considered to be limited to the specific construction herein shown and described but may be varied insofar as it does not depart from the scope of the appended claims. It is within the purview of the invention, for example, to employ an abrasive element in the form of a grinding roll in place of a travelling belt, in which case the positions of the axes which are defined as being respectively perpendicular and parallel to the abrasive surface, will be considered to be substantially perpendicular and parallel to a tangent plane of the abrasive surface at the position of contact of the abrasive element with the work.

Having thus described the invention, what is claimed is:

1. A grinding or polishing machine having, in combination, a work rest, an abrasive element, a work holding and feeding device to engage peripherally with the work and to feed it transversely of the abrasive element, and means for mounting the abrasive element and the work holding and feeding device having provision for recessive movement between them, and means for causing relative movement between the work holding and feeding device and the abrasive element as the grinding or polishing proceeds to accommodate taper work.

2. A grinding or polishing machine having, in combination, a work rest, an abrasive element, a work holding device for peripherally supporting the work, and means for rotatably adjusting the work holding device about an axis substantially parallel to the direction of movement of the abrading surface to accommodate work of non-uniform diameter.

3. A grinding or polishing machine having, in combination, an abrasive element, a work rest, feed roll for peripherally supporting the work in engagement with the abrasive element and for feeding the work transversely of the abrasive element, and means for causing recessive movement of the feed roll from the abrasive element during feeding of the work to accommodate work of non-uniform diameter.

4. A grinding or polishing machine having, in combination, an abrasive element, a work rest, a feed roll for feeding the work transversely of the abrasive element and for maintaining it in engagement therewith, means for adjusting the inclination of the feed roll about an axis substantially perpendicular to the abrasive element, and means for mounting the feed roll having provision for progressively varying the distance between the feed roll and the abrasive element to accommodate work of changing diameter.

5. A grinding or polishing machine having, in combination, an abrasive element, a work rest, a feed roll for feeding the work transversely of the abrasive element and for maintaining it in engagement therewith, means for adjusting the inclination of the feed roll about an axis substantially perpendicular to the abrasive element, and means for causing the feed roll to recede from the abrasive element as the grinding progresses to accommodate work of increasing diameter. 70
10. A grinding or polishing machine having, in combination, an abrasive element, a work rest, a feed roll for feeding the work transversely of the abrasive element and for maintaining it in engagement therewith, means for adjusting the inclination of the feed roll about an axis substantially perpendicular to the abrasive element, means for causing progressive movement of the carriage on the slide bearing as the feeding of the work proceeds to permit grinding or polishing of taper articles. 75
15. A grinding or polishing machine having, in combination, an abrasive element, a work rest, a feed roll for feeding the work transversely of the abrasive element and for maintaining it in engagement therewith, means for adjusting the inclination of the feed roll about an axis substantially perpendicular to the abrasive element, means for rotating the feed roll, means for slidably mounting the feed roll, means for progressively moving the feed roll from or toward the abrasive element as the grinding progresses, and means for maintaining the feed roll in engagement with the work irrespective of the variations in diameter of the work. 80
20. A grinding or polishing machine having, in combination, an abrasive element, a work rest, a feed roll, means for mounting the feed roll having provision for tilting thereof about axes substantially perpendicular and parallel to the abrading surface, and means for permitting the feed roll to recede from the abrading element as the grinding progresses. 85
25. A grinding or polishing machine having, in combination, an abrasive element, a work rest, a feed roll assembly including a rotating feed roll adapted to engage with and to feed the work, a slide bearing having provision for permitting the feed roll assembly to slide back and forth with relation to the abrasive element, a support for the slide bearing arranged at one side of the bearing, a weight and connections therewith for maintaining the feed roll in engagement with the work, the weight being positioned at the opposite side of the support on the slide bearing to counter-balance the latter. 90
30. A grinding or polishing machine having, in combination, an abrasive element, a feed roll adapted to engage the work on the opposite side from the abrasive element and having provision for tipping about mutually perpendicular axes which are substantially perpendicular to the axis of rotation of the feed roll, a sliding carriage on which the feed roll is mounted and adapted to move away from the abrasive element during feeding and grinding of taper work, and means for locking the carriage for grinding of straight work or of taper work without feeding. 95
35. A grinding or polishing machine having, in combination, an abrasive element, a work rest, a feed roll to feed the work transversely of the abrasive element, means for permitting tipping of the feed roll on mutually perpendicular axes which are substantially perpendicular to the axis of rotation of the feed roll, a slide bearing in which the carriage is free to move toward or away from the abrasive element during transverse feed of the work to permit grinding or polishing of tapers. 100
40. A grinding or polishing machine having, in combination, an abrasive element, a work rest, a feed roll, means for maintaining the work in engagement with the abrasive element, and means for adjusting the work rest to different angular positions to vary the angle between the plane of the work rest and the abrading surface. 105
45. A grinding or polishing machine having, in combination, an abrasive element, a feed roll, a table for supporting the feed roll, a work rest, work rest supporting means extending outwardly from the table and constructed and arranged to effect a simultaneous vertical and horizontal adjustment of the work rest, and means for mounting the work rest supporting means having provision for an angular adjustment of the plane of the work rest. 110
50. A grinding or polishing machine having, in combination, an abrasive element, a feed roll adapted to engage the work on the opposite side from the abrasive element and having provision for tipping about mutually perpendicular axes which are substantially perpendicular to the axis of rotation, a work rest, a support for the feed roll having provision for permitting bodily recession of the feed roll from the abrasive element for grinding or polishing tapers, and means for maintaining the feed roll in engagement with the work during the grinding or polishing operation. 115
55. A grinding or polishing machine having, in combination, an abrasive element, a feed roll, a table for supporting the feed roll, a work rest, work rest supporting means extending outwardly from the table and constructed and arranged to effect a simultaneous vertical and horizontal adjustment of the work rest, and means for mounting the work rest supporting means having provision for an angular adjustment of the plane of the work rest. 120
60. A grinding or polishing machine having, in combination, an abrasive element, a feed roll, a table for supporting the feed roll, a work rest, work rest supporting means extending outwardly from the table and constructed and arranged to effect a simultaneous vertical and horizontal adjustment of the work rest, and means for mounting the work rest supporting means having provision for an angular adjustment of the plane of the work rest. 125
65. A grinding or polishing machine having, in combination, an abrasive element, a feed roll, a table for supporting the feed roll, a work rest, work rest supporting means extending outwardly from the table and constructed and arranged to effect a simultaneous vertical and horizontal adjustment of the work rest, and means for mounting the work rest supporting means having provision for an angular adjustment of the plane of the work rest. 130

feed roll to feed the work transversely of the abrasive element, a work rest, a slide bearing for the feed roll, means for causing the feed roll to recede progressively from the abrasive element during feeding of the work to accommodate taper work. 70

11. A grinding or polishing machine having, in combination, an abrasive element, a work rest, a feed roll to feed the work transversely of the abrasive element, a feed roll pivoted on an axis substantially perpendicular to the abrading surface, a carriage on which the housing is mounted, a slide bearing in which the carriage has provision for longitudinal movement toward and away from the abrasive element, and means for causing progressive movement of the carriage on the slide bearing as the feeding of the work proceeds to permit grinding or polishing of taper articles. 80

12. A grinding or polishing machine having, in combination, an abrasive element, a work rest, a feed roll to feed the work transversely of the abrasive element, a feed roll carriage, means for mounting the feed roll on the carriage having provision for tipping of the roll on axes substantially perpendicular and parallel to the abrading surface respectively, and a slide bearing in which the carriage is free to move toward or away from the abrasive element during transverse feed of the work to permit grinding or polishing of tapers. 90

13. A grinding or polishing machine having, in combination, an abrasive element, a work rest, a feed roll to feed the work transversely of the abrasive element, means permitting tipping of the feed roll on mutually perpendicular axes which are substantially perpendicular to the axis of rotation of the feed roll, a sliding carriage on which the feed roll is mounted and adapted to move away from the abrasive element during feeding and grinding of taper work, and means for locking the carriage for grinding of straight work or of taper work without feeding. 100

14. A grinding or polishing machine having, in combination, an abrasive element, a work rest, means for maintaining the work in engagement with the abrasive element, and means for adjusting the work rest to different angular positions to vary the angle between the plane of the work rest and the abrading surface. 110

15. A grinding or polishing machine having, in combination, an abrasive element, a feed roll, a table for supporting the feed roll, a work rest, work rest supporting means extending outwardly from the table and constructed and arranged to effect a simultaneous vertical and horizontal adjustment of the work rest, and means for mounting the work rest supporting means having provision for an angular adjustment of the plane of the work rest. 120

work rest with respect to the abrasive element.

16. A grinding or polishing machine having, in combination, an abrasive element, a feed roll, a table for supporting the feed roll, a work rest, a work rest supporting post extending on an angle from the table and toward the abrasive element, a bushing secured to the table, a rack formed on the supporting post, a pinion engaging with the rack for adjusting the position of the work rest, and means for locking the work rest in adjusted position.

17. A grinding or polishing machine having, in combination, an abrasive element, a feed roll, a table for supporting the feed roll, a work rest, a work rest supporting post having a circular rack formed on one end, a bushing secured to the table and receiving the supporting post, a pinion engaging with the rack for adjusting the work rest and permitting turning adjustments of the work rest, and means for clamping the supported post.

18. A work rest for a centerless grinding or polishing machine, comprising a series of rollers with which the work engages, a pintle having its axis below and substantially parallel with the work on which the rollers are mounted for free rotation, and a support for the pintle.

19. A work rest for a centerless grinding or polishing machine, comprising a supporting plate having a plurality of upwardly extending projections, a pintle extending through the projections, and a series of freely rotatable rollers mounted on the pintle between the projections for supporting the work.

20. A grinding or polishing machine having, in combination, an abrasive element, a work holding and feeding device, a pulley for the work holding and feeding device, means permitting longitudinal and inclined movements of the work holding and feeding device, a belt associated with the pulley for operating the device, means for maintaining the belt taut including spaced idler pulleys adapted for simultaneous movement, and means for maintaining the idler pulleys in engagement with opposite sides of the belt and under sufficient pressure to tension the belt.

21. A grinding or polishing machine having, in combination, an abrasive element, a feed roll, a feed roll carriage to permit movement of the feed roll with respect to the abrasive element, means permitting inclination of the feed roll, a belt for driving the feed roll, an idler arm, a pair of spaced idler pulleys mounted on the idler arm and adapted for simultaneous movement, and a counter balance associated with the idler arm for maintaining the idler pulleys in engagement with opposite sides of the belt under suffi-

cient pressure to maintain the belt taut at all positions of the feed roll.

22. A grinding or polishing machine having, in combination, an abrasive element, a work holding and feeding device, a carriage to permit movement of the work holding and feeding device with respect to the abrasive element, a belt for driving the work holding and feeding device, means for maintaining the belt taut at all positions of the carriage including an idler pulley and a counter balance, and means for mounting the counter balance having provision for permitting a decrease in the tensioning effect on the belt as the carriage recedes from the abrasive element.

In testimony whereof I have signed my name to this specification.

RUFUS W. FULLER.
